(57) CLAIM

The ornamental design for a card wallet as shown and described.

DESCRIPTION

FIG. 1 is a perspective view of a card wallet, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines in the drawing figures depict portions of the card wallet that form no part of the claimed design.

The dot-dash broken lines shown in FIGS. 1-3 depict stitching which form a part of the claimed design.

1 Claim, 7 Drawing Sheets
